UNITED STATES PATENT OFFICE.

CLARENCE M. CREWS, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed September 27, 1924. Serial No. 740,172.

This invention relates to means for quickly feeding work-sheets into a typewriting machine from the front of the platen.

In banks and other business houses records of periodic payments are frequently kept upon record cards which have metallic or other filing tabs projecting from their upper margins. For this class of work, which is cited merely as an example, it is extremely desirable to provide means whereby the work can be quickly located in writing position by feeding it into the machine bottom end first at the front of the platen.

In accordance with the present invention provision is made of a work-feeder comprising a funnel mouthed gripper extending across the front of the platen above the line of writing. This gripper is arranged to be rotated independently of the platen, in an anti-line-feed direction, when a work-sheet or pack of sheets has been placed in it, to draw the work down around the platen. Provision is made of means for sweeping the gripper always through a uniform range of one complete revolution, so that at one continuous movement the gripper carries the work into the machine and returns to its initial normal position without retrograde movement. The work is released by the gripper after it has been fed into the machine and may then be fed by the platen to any desired writing position, the further control of the work being altogether independent of the feeder, which remains stationary until a succeeding sheet is placed in it for insertion in the machine. The gripper-operating means is constructed to return to initial position, when released, without moving the gripper.

Other features and advantages will hereinafter appear.

In the accompanying drawings,

Figure 1 is a fragmentary front elevation, showing the present invention applied to the platen-frame of an Underwood Standard typewriter.

Figure 2 is a longitudinal vertical section, showing the mechanism shown in Figure 1, the parts being in their normal positions.

Figure 3 is a view similar to Figure 2, but shows the parts in operation at the point where the gripper has emerged from the bight formed by the platen and the rear paper-table.

Figure 4 is a view similar to Figures 2 and 3, showing the parts in normal positions, and the work-sheet in writing position. The figure also shows in dot-and-dash lines the position to which the work-sheet was inserted by the gripper before being adjusted to writing position by the platen and the feed-rolls.

Figure 5 is a transverse vertical section, showing details of the gripper-driving mechanism.

In the typewriting machine types 10 strike upwardly and rearwardly through a ribbon 11 against the face of a cylindrical platen 12 journaled by its axle 13 in the ends 14 of a platen-frame 15. Feed-rolls 16 co-operate with the lower face of the platen 12 through openings 17 in a paper-apron 18 that forms a lower extension of a rear paper-table 19, and that snugly embraces the platen. The feed-rolls 16 may be cast off by means usually provided for the purpose, but not shown herein.

The novel sheet-feeder consists of an arcuate strip 20 of thin spring metal which extends across the platen in close proximity to it, but in position to move freely relatively to the platen. This arcuate strip 20 forms the inner wall of a work-receiving gripper or pocket and is folded back sharply at its forward end to form the front wall 21 of said pocket. This forward wall 21 of the pocket flares outwardly from the main body of the arcuate strip to form a fluted mouth for the reception of the work. The wall 21 is very thin and flexible, so that a work-sheet 22 can spring it outward slightly and can therefore be easily inserted in the pocket. The wall 21 can also be pressed inward toward the platen by any parts with which it comes in contact to grip the work and to avoid fouling upon such parts. The strip 20 has flanges 22a at its ends whereby it is secured to segments 23 and 24 rotatably mounted upon the platen-axle 13 just beyond the ends of the platen 12. A handle 25 mounted upon a stub-shaft 26, carried by a bracket 27 on the platen-frame 15, drives a gear 28 in mesh with a pinion 29 loose on the platen-axle 13. This pinion 29 is fast to a ratchet 30 which is effective through a pawl 31 on the segment 24, held in engagement with the ratchet 30 by a spring 32, to drive the segment 24, and hence the work-feeder, in a clockwise direction, as seen in

95

90

100

105

Figure 2, when the handle 25 is thrust to the rear. The parts normally occupy the positions shown in Figure 2, with the gear 28 held against a rear stop 33 on the bracket 5 27 by a spring 34, and with the feeder detained in the position shown by a spring-detent 35 on the bracket 27 that engages a pin 36 on the segment 24.

When it is desired to insert a work-sheet 10 22 into the machine from the front, the sheet is placed with its lower edge in the pocket of the feeder, and the handle 25 is moved to the rear until arrested by engagement of the gear 28 with a fixed stop 37 on the bracket 15 27. This carries the feeder-gripper through a complete revolution, restoring the gripper to the position shown in Figure 2. The handle 25 is then released and is restored to its original position by the spring 34, the 20 pinion 29 and ratchet 30 being rotated meanwhile by the gear 28, but not in a direction to drive the feeder, which remains stationary.

As the feeder is moved around the platen 25 in the act of inserting a work-sheet, there is a liability that it will foul the ribbon 11. Provision is accordingly made of a wire guide 38, mounted on the usual type-segment 39, which stands between the ribbon 30 11 and the platen 12 to guard the ribbon. This guide 38 serves the further function of pressing the wall 21 of the gripper toward the platen and thereby increasing the grip upon the paper in the first part of the 35 inserting operation. The lower edge 40 of the gripper is perfectly straight and quite thin, and hugs the platen closely. It has no difficulty therefore in wedging its way beneath the flared forward edge of the 40 paper-apron or beneath the feed-rolls, if they are not cast off. The paper-apron presses the wall of the gripper toward the platen to increase its grip upon the paper, and this firm grip is maintained until the 45 gripper has reached the position shown in Figure 3. At this point the gripper emerges from the bight formed by the rear paper-table and the platen, releasing the sheet. At the same time the trailing edge 41 of the 50 gripper passes to the rear of the front feed-rolls 16, permitting the rolls to coact with the platen to grip the inserted sheet 22 and hold it stationary. The sheet is therefore held in the dot-and-dash position 22' of Figure 4, while the gripper travels from the 55 position of Figure 3 to that of Figure 4. When the gripper finally reaches the position of Figure 4, the handle is arrested, and at the same time the detent and projection 60 come into co-operative relation to hold the gripper stationary. The platen is then rotated by one of the knobs 42 to adjust the inserted sheet 22 to writing position.

It will be noted that the feeder may be 65 used with the feed-rolls 16 either effective

or ineffective. In order that the sheet may be correctly positioned when placed in the gripper, so that casting off of the feed-rolls subsequently to the insertion of the sheet may be obviated, provision is made of a letter-space scale on the front face of the wall 21 of the feeder. This is especially advantageous for the reason that work of the character for which the feeder is designed is frequently done upon bookkeeping machines, so that it is of the utmost importance that the columns on the sheet register correctly with the computing columns of the computing mechanism at every insertion.

The feeder may be used to advantage for work of any class requiring insertion from the front of the platen, such, for example, as work-sheets held together in a pack by means of a clip at their upper margins.

Variations may be resorted to within the scope of the invention, and portions of the improvements may be used without others.

Having thus described my invention, I claim:

1. In a typewriting machine, the combination with a cylindrical platen, of a gripper constructed to grip a sheet at the front of the platen, and means independent of the platen to operate the gripper to draw the gripped sheet backward around the platen into the machine.

2. In a typewriting machine, the combination with a cylindrical platen, of a gripper constructed to grip a sheet at the front of the platen, means independent of the platen to operate the gripper to draw the gripped sheet backward around the platen into the machine, and means to hold the gripper stationary and out of the way during adjustment and feeding of the inserted sheet by the platen.

3. In a typewriting machine, the combination with a cylindrical platen, of a feeder comprising a relatively stiff inner wall adjacent the platen and a resilient flaring outer wall, the two walls forming a wide mouthed pocket for the reception of work-sheets, means for rotating the feeder in an anti-line-feed direction to draw work into the machine from the front of the platen, and a guard to prevent fouling of the ribbon by the feeder, the guard being arranged also to press the outer wall of the feeder into firm gripping relation to the work.

4. In a typewriting machine, the combination with a cylindrical platen, of a feeder comprising a relatively stiff inner wall adjacent the platen and a resilient flaring outer wall, the two walls forming a wide mouthed pocket for the reception of work-sheets, and means for rotating the feeder in an anti-line-feed direction to draw work into the machine from the front of the platen, and a paper-apron conforming to the lower side of the

- platens, the paper-apron having its forward edge flared outward to enable the feeder to wedge itself between the apron and the platen in inserting work in the machine.
5. In a typewriting machine, the combination with a cylindrical platen, of a feeder comprising a gripper, and means for rotating the gripper through a complete revolution in an anti-line-feed direction to draw work into the machine, the gripper-rotating means being arranged to be returned to normal position while permitting the gripper to remain stationary.
6. In a typewriting machine, the combination with a cylindrical platen, of a feeder comprising a gripper, and means for rotating the gripper through a complete revolution in an anti-line-feed direction to draw work into the machine, a spring to return the gripper-rotating means to initial position, and a detent to hold the gripper stationary during the return of the gripper-rotating means to initial position.
7. In a typewriting machine, the combination with a cylindrical platen, of a feeder comprising a gripper, a sweep-gear having a one-way driving connection with the gripper for driving it in anti-line-feed direction to feed work into the machine from the front of the platen, means for mechanically limiting the stroke of the sweep-gear to cause the gripper to be carried through a complete revolution to its initial position at each full actuation of the gear, and means for returning the gear to initial position while the gripper remains idle.
8. In a typewriting machine, the combination with a cylindrical platen and feed-rolls co-operating therewith, of a sheet-feeder operable relatively to the platen to draw a work-sheet into the machine from the front of the platen, said feeder comprising a gripper having a flaring resilient outer wall, the outer wall bearing a letter-space scale to enable the operator to position the sheet correctly in the gripper before inserting it in the machine.
9. In a typewriting machine, the combination with a platen, front feed-rolls co-operating therewith, and a paper-apron forming thereto, of a sheet-feeder rotatable about the platen in an anti-line-feed direction to insert work-sheets in the machine from the front of the platen, the feeder comprising a gripper having a long relatively stiff arcuate inner wall and a thin resilient flaring outer wall arranged to be pressed toward the inner wall by the paper-apron to grip the work securely, the inner wall being long enough to hold the front feed-rolls off the platen until the outer wall of the gripper has emerged from the bight formed by the platen and the paper-apron, and then to pass beyond the front feed-rolls to permit them to coact with the platen to hold the inserted sheets stationary and withdraw them from the gripper.
10. In a typewriting machine, the combination with a platen, of a feeder for drawing work-sheets into the machine from the front of the platen comprising a gripper including a flaring resilient outer wall normally arranged to grip the work with light pressure, means to engage the outer wall of the gripper as it is rotated to press it into firm gripping engagement with the work, and means to grip the work and hold it stationary when the gripper has passed beyond said pressing means, thereby withdrawing the work from the gripper.
11. In a typewriting machine, the combination with a platen, of a work-feeder for drawing work-sheets into the machine, comprising a gripper having a relatively stiff inner wall and a relatively flexible resilient outer wall turned back along the inner wall, the outer wall being looped in toward the inner wall to provide a gripping portion and being then flared outward to provide a funnel-like opening for receiving work, and means for engaging the outwardly-flared portion of the outer wall to press it closely against the inner wall and thereby increase the grip of the gripping portion upon the work.
